UNITED STATES PATENT OFFICE.

VERNON L. MATTSON, OF SOUTH CHARLESTON, WEST VIRGINIA.

MATHEMATICAL INSTRUMENT.

1,419,283.

Specification of Letters Patent. Patented June 13, 1922.

Application filed January 3, 1920. Serial No. 349,272.

To all whom it may concern:

Be it known that I, VERNON L. MATTSON, a citizen of the United States, residing at South Charleston, in the county of Kanawha 5 and State of West Virginia, have invented new and useful Improvements in Mathematical Instruments, of which the following is a specification.

This invention relates to mathematical 10 instruments mainly designed for surveyors and the principal object of the invention is to provide means for computing the sine and cosine of an angle when the degree of the angle and the length of the hypotenuse is 15 known.

While the invention is more particularly 20 designed for use by surveyors it will of course be understood that the device may be used in other situations and for other purposes.

This invention also consists in certain other features of construction and in the combination and arrangement of the several parts, to be hereinafter fully described, 25 illustrated in the accompanying drawings and specifically pointed out in the appended claims.

In describing my invention in detail, reference will be had to the accompanying 30 drawings wherein like characters denote like or corresponding parts throughout the several views, and in which:—

Figure 1 is a plan view with parts broken away.

35 - Figure 2 is a section on line 2—2 of Figure 1.

Figure 3 is a detail view of the stationary and movable arms.

Figure 4 is a section on line 4—4 of Figure 5.

40 Figure 5 is a section on line 5—5 of Figure 4.

Figure 6 is a diagrammatic view.

As shown in these views 1 indicates a casing 45 which is preferably of the shape shown in Figure 1, which shows the casing as having one side formed in an arc of a circle. This edge may be provided with the scale 2 which is divided into degrees, minutes and 50 seconds. This casing is provided with a cover 3 which extends over part of the casing. This cover rotatably supports the crank shaft 4 which carries the gear wheel 5. The cover, upon its inner face is pro-

vided with the tubular boss 6 which receives 55 the shaft 7 to which is secured the upper disc 8 and the small gear 9, said gear meshing with the gear 5. The spring 10, located in the boss, tends to force the shaft and its disc downwardly. A similar boss 11 is 60 formed on the bottom of the casing and a stationary shaft 12 is supported within said boss. A lower disc 13 is provided with a tubular hub 14 which surrounds the shaft 12 and is mounted within the boss 11. A 65 spring 15 in said boss tends to force the disc and its hub upwardly. As will be seen the upper and lower discs have their centers out of alignment, though said discs overlap, as shown. The discs are provided with teeth 70 16 on their circumference and the discs are geared together by the toothed wheels 17 located on the stub shaft 18 which is suitably supported in the casing. In this way when the crank shaft is turned both discs 75 will be rotated.

A stationary arm 19 has its inner end supported on the shaft 12 and its other end resting on the curved edge of the casing. The inner end of this arm is provided with 80 a socket 20 and this socket is engaged by the rounded end of a movable arm 21 which is pivoted to the upper end of the shaft 12 within said socket. The outer end of this movable arm extends over the curved edge 85 of the case and is provided with the vernier 22 which cooperated with the scale 2. A cross arm 23 is pivotally connected at 24 to the stationary arm 19 and this cross arm is slotted as at 25 to receive the arm 21. A 90 T-shaped head 26 is slidably mounted on the arm 21 and on the arm 23, said arms 21 and 23 passing through the head at right angles to each other as shown. The head is provided with openings for receiving said arms 95 so that both arms are embraced by the head. The head carries friction rollers 27 for engaging the arms. The arm 21 has upper and lower notches on its front face forming the tongue 28, said notches receiving the 100 rollers on the front face of the head. As will be seen the arms are located between the discs.

The head is provided with upper and lower brackets 29, which carry the tractor 105 wheels 30. A shaft 31 passes through the upper bracket and its tractor wheel is keyed to said shaft so that it may slide thereon and

a shaft 32 passes through the other bracket and the wheel of this bracket is keyed to this shaft. These shafts 31 and 32 extend at rightangles to each other and the wheels are 5 arranged at rightangles to each other. The upper shaft 31 is connected with the counter mechanism 33 while the lower shaft 32 is connected with the counter mechanism 34. The upper shaft and its counter mechanism 10 is carried by the cross arm 23 while the lower shaft and its counter mechanism is carried by the movable arm 21. The outer end of the cross arm is slidably mounted on a part of the cover. The edge of the tongue 15 28 forms a straight edge which is in the same plane as the circumferential center of the wheel 30. Both counter mechanisms are so arranged that they will indicate each revolution of the wheels 30 and as will be 20 seen these wheels are engaged by the upper and lower discs which are frictionally held in engagement with said wheels by the springs 10 and 15. Thus as the discs are rotated the wheels will revolve, causing the 25 shafts to rotate and thus actuate the counter mechanisms. As the T-shaped head is moved the wheels will slide upon the shafts.

Counter mechanism 35 is located on the outer end of the stationary arm and the 30 shaft 36 of this mechanism has its inner end journaled in a bracket 37 located on said arm under the upper disc 8. A wheel 38 is secured to this shaft and engages the underface of said upper disc.

35 Supposing a surveyor has run a line 220 feet with its extremity 30° due east. He will then have an angle such as A, B, C in Figure 6 of 30° , the hypotenuse of which is 220 feet in length. He has to then find out the length of A, C and C, B. In computing the 40 length of these lines on my instrument the surveyor would first move the movable arm 21 to the 30° mark on the scale. Then he would rotate the crank 4 until the numbers 220 appeared in the counter 35. This movement of the upper and lower discs would cause the wheels 30 to actuate their counters to indicate the length of lines A, C and C, B, the counter 34 giving the cosine of the angle 45 multiplied by the length of the hypotenuse 220 and counter 33 the sine of the angle multiplied by 220.

As the arm 21 is moved the arm 23 and the head 26 will also be moved, the head sliding on arm 21 and also on arm 23, this movement will move the wheels 30 upon their shafts and relatively to the centers of the discs so that said wheels will be rotated more or less by the movement of said discs 60 according to their positions on the discs.

I may provide suitable means for pressing the discs apart and out of contact with the wheels when the arms are to be moved. As shown such means consists of a handle 40 65 connected with the shaft 7 and passing

through the cover so that said shaft and its disc may be raised and a lever 41 pivoted in the side of the casing and engaging the lower disc so that said lower disc may be lowered.

70 As before stated my instrument is mainly designed for surveyors but it will of course be understood that it may be used for securing the cosine and sine multiplied by one side of the triangle where the degree of the angle and length of one side is known, or any side of a right triangle where one side and either angle is known.

75 Attention is called to the fact that the pivotal point of the cross arm is in alignment with the center of the upper disc.

What I claim is:—

1. An instrument of the class described comprising a pair of spaced rotatable elements, means for rotating said elements in unison, setting means actuated by one element by having a part engaging the inner face thereof, said means indicating the length of the known side of a right triangle, a pair of counter mechanisms actuated by 85 said rotary elements for indicating the lengths of the other sides of the triangle, said mechanisms having portions located between the elements and engaging the inner faces thereof and setting means for the said 90 mechanisms movable to correspond with the degree of the angle.

2. An instrument of the class described comprising a pair of spaced rotary elements, manually actuated means for rotating said elements in unison, indicating means actuated by one of the elements for indicating when said elements have been moved to a position correspondent to the known length of one side of a right triangle, a pair of counter mechanisms for indicating the 100 lengths of the other sides, means for actuating said mechanisms by the movement of the elements, said means including parts located between the elements and engaging the inner faces thereof and means for adjusting the actuating means relative to the elements in accordance with the degree of the angle.

105 3. An instrument of the class described comprising a pair of spaced rotary elements, manually actuated means for rotating said elements in unison, indicating means actuated by one of the elements for indicating when said elements have been moved to a degree correspondent to the known length of one side of a right triangle, a pair of counter mechanisms for indicating the lengths of the other sides, means for actuating said mechanisms by the movement of the elements, said 110 means including parts arranged between the elements and engaging the inner faces thereof and means for adjusting the actuating means relative to the elements in accordance with the degree of the angle, such 115 120 125 130

means comprising movable arms to which the actuating means are attached, a stationary scale and a marker on one of the movable arms for cooperating with the scale.

- 5 4. An instrument of the class described comprising a casing, a pair of discs rotatably supported in said casing, said discs having their centers out of alignment, manually actuated means for rotating said discs
 10 in unison, a stationary arm extending between the discs, a manually movable arm pivotally connected to the end of the stationary arm, a head slidably mounted on said movable arm, a cross arm having one end pivotally connected with the stationary arm and extending at an angle therefrom and slidably connected with the head for causing said cross arm to be moved with the manually operated arm, upper and lower wheels carried
 15 by said head and engaging the upper and lower discs so as to be rotated thereby, counter mechanism connected with each wheel, a scale and marker associated with the movable arm for facilitating the proper
 20 adjustments of the wheels on the head relative to the discs, a setting counter mechanism and means for actuating the same by the upper disc, said setting counter mechanism indicating when the discs have been
 25 30 moved sufficiently to rotate the wheels to

cause their counter devices to give the desired results.

5. An instrument of the class described comprising a casing, upper and lower discs rotatably supported therein and having their centers out of alignment, means for rotating said pair of discs in unison, a stationary arm extending between the discs, a movable arm having one end pivotally connected with the stationary arm, a head slidably mounted on said movable arm, a cross arm having one end pivotally connected to the stationary arm and slidably connected with the head, upper and lower wheels carried by said head and engaging with the discs so as to be rotated by the movement of said discs, counter mechanisms each having a shaft slidably engaging the wheels, said shafts actuating the counter mechanisms when the wheels are rotated, a setting counter mechanism actuated by the upper disc for indicating when the discs have been moved to a position to solve the problem and a scale and marker associated with the movable arm for indicating when said arm has been moved to properly adjust the wheels on the head in relation to the discs.

In testimony whereof I affix my signature.

VERNON L. MATTSON.
